(57) **CLAIM**

The ornamental design for the headset packaging insert, as shown and described.

DESCRIPTION

FIG. 1 is a front perspective view depicting a headset packaging insert having an insert top and an insert bottom according to the present invention;

FIG. 2 is a top plan view depicting an inside of the insert top and insert bottom shown in FIG. 1;

FIG. 3 is a bottom plan view depicting an outside of the insert top and insert bottom shown in FIG. 1;

FIGS. 4 and 5 are side elevational views depicting a right-hand side and a left-hand side, respectively, of the insert top and insert bottom shown in FIG. 1;

FIGS. 6 and 7 are front and rear elevational views, respectively, of the insert top and insert bottom shown in FIG. 1;

FIG. 8 is a front perspective view of the headset packaging insert of FIG. 1, shown in combination with unclaimed structures with which the design may be used; and,

FIG. 9 is a sectional view depicting a portion of the insert top and an insert bottom of FIG. 2 and shown along line 9-9.
